UNITED STATES PATENT OFFICE.

THOMAS TOWNSON, OF PHILADELPHIA, PENNSYLVANIA.

AUTOMATIC SPARK-TIMING MECHANISM FOR INTERNAL-COMBUSTION ENGINES.

1,025,336.

Specification of Letters Patent.

Patented May 7, 1912.

Application filed June 1, 1911. Serial No. 630,638.

To all whom it may concern.

Be it known that I, THOMAS TOWNSON, a citizen of the United States, residing at Philadelphia, in the county of Philadelphia and State of Pennsylvania, have invented 5 certain new and useful Improvements in Automatic Spark-Timing Mechanism for Internal-Combustion Engines, of which the following is a specification.

10 My invention relates to improvements in automatic spark timing mechanism for internal combustion engines, the object of the invention being to provide an improved governor connected with the spark timer, 15 whereby the speed of the engine automatically advances or retards the spark in the respective cylinders.

Heretofore, it has been customary with motor propelled vehicles to provide on the 20 steering wheel, a lever for regulating the gas, and a lever for advancing and retarding the spark, leaving it therefore to the judgment of the operator to regulate the spark properly in accordance with the feed 25 of gas. To dispense altogether with this lever for regulating the spark, and rendering such regulation automatic, is the primary object of my invention, and it consists of certain novel features of construction 30 and combinations and arrangements of parts, as will be more fully hereinafter described and pointed out in the claims.

In the accompanying drawings: Figure 1, 35 is a diagrammatic plan view illustrating my improvements, and Fig. 2, is a view in section on the line 2--2 of Fig. 1.

1, represents the aft time shaft of an internal combustion engine mounted in a suitable support 2, and operating the spark timing mechanism 3.

40 This spark timer may be of various different forms and I have illustrated a simple structure which is adapted to answer the purposes of my invention, and the spark timer that I have illustrated is provided 45 with four binding posts 4 which are connected by wires 5 with the respective engine cylinders, and the inner ends of said binding posts are connected with contact blocks 6, 50 all of which are mounted in a rotary sleeve 7 in a fixed casing 8.

On the time shaft 1, a rotary spring- 55 pressed contact lever 9 is mounted, and as the time shaft revolves, this contact 9 is moved into and out of contact with the several contacts 6, so as to momentarily close

the circuits with the respective cylinders to fire the charge in the latter. A bracket 10 is secured to support 2, and provides a bearing for a shaft 11. This shaft 11 is connected by beveled gears 12 and 13 with time shaft 1, so that shaft 11 is driven at the same speed as the time shaft. On shaft 11, a speed governor is located, and comprises weighted arms 13^a pivotally connected to 60 the shaft 11, and connected by links 14 with a sliding sleeve 15. This sleeve 15 is provided with a grooved enlargement 16 into which the bifurcated end 17 of a rod 18 projects. Rod 18 is mounted to slide in the 65 bracket 10, and is connected at one end to a pin 19 fixed to the rotary sleeve 7. On this rod 18, a coiled spring 20 is located, and its tension is adjusted by means of nuts 21 70 screwed onto the threaded portion of said rod. By means of this spring, a nice adjustment may be had to resist the longitudinal movement of sleeve 15, as the weighted arms 13^a tend to draw the sleeve longitudinally of the shaft in accordance with the 75 speed of time shaft 1. As the speed of time shaft 1 increases, the governor will move sleeve 15 longitudinally of the shaft, and through the medium of rod 18, will turn sleeve 7 so as to advance the spark as is 80 readily understood. In other words, the speed of shaft 1, through the medium of the 85 governor, automatically advances or retards the spark in the several cylinders.

Various slight changes might be made in 90 the general form and arrangements of parts described without departing from my invention, and hence I do not limit myself to the precise details set forth, but consider myself at liberty to make such changes and alterations as fairly fall within the spirit and 95 scope of the appended claims.

Having thus described my invention, what I claim as new and desire to secure by Letters Patent is:

1. The combination with a support, an 100 engine time shaft, a spark timing mechanism thereon, a sleeve in said mechanism, electric contacts in said sleeve, said time shaft mounted in the support, a rotary element on the time shaft adapted to engage respectively the several contacts, a bracket on said support, a shaft mounted in said bracket and located at right angles to the time shaft, and gears connecting said time 105 shaft and said last-mentioned shaft, of a sleeve mounted on the last-mentioned shaft,

weighted arms pivotally connected to said last-mentioned shaft, links connecting said arms and sleeve, a rod mounted in said bracket, said sleeve having a groove therein, 5 a forked end on said rod engaging said groove, and a pin on the first-mentioned sleeve connected to said rod, substantially as described.

2. The combination with a support, a 10 spark timing mechanism, a sleeve in said mechanism, electric contacts in said sleeve, a time shaft mounted in the support, a rotary element on the time shaft adapted to engage respectively the several contacts, a 15 bracket on said support, a shaft mounted in said bracket and located at right angles to the time shaft, and gears connecting said time shaft and said last-mentioned shaft, of a sleeve mounted on the last-mentioned 20 shaft, weighted arms pivotally connected to

said last-mentioned shaft, links connecting said arms and sleeve, a rod mounted in said bracket, said sleeve having a groove therein, a forked end on said rod engaging said groove, a pin on the first-mentioned sleeve 25 connected to said rod, said rod screw-threaded at its end where it connects with the pin, a spring around said rod and bearing at one end against the bracket, and a nut screwed on the rod and bearing against the other 30 end of said spring, substantially as described.

In testimony whereof I have signed my name to this specification in the presence of two subscribing witnesses.

THOMAS TOWNSON.
